cuse, N. Y., a corporation of New York

Application January 11, 1946, Serial No. 640,657

4 Claims. (Cl. 121—38)

1

This invention relates to controls for presses or power machines having successive or repeated operating movements, as for one example, an opening and closing movement, during each operation on a piece of work. In some of such machines, as for example, laundry and garment presses, the machine stops when in closed position of each operating movement, or has two steps, a closing step and an opening step in each operation, and the machine remains closed for a period before opening. In other machines, as punch presses, the operation is in one continuous movement, that is, the closing and opening is without a pause. In other machines, the operations may be intermittent in one direction only, as in a rotary cut-off or shearing tool. When there is a pause at the end of the closing movement, releasable holding or stopping means are used in the event it is desired to relieve the operator of holding the manuals operated, while the machine is closed. The control mechanism of this invention is particularly adapted for the punch press operation, although, of course, it is adapted to the type of operations used in garment and laundry presses.

The invention has for its object locking mechanism for each manually-operated member of a two hand control in which the locking of either member is controlled by the operation of the other member when only the latter member is operated, so that the machine can not be operated by the operation of one manual only.

The invention further has for its object a construction by which repetition of the operating movements of the machine is positively prevented, if the operator holds the manuals continuously operated, that is, a mechanism which temporarily disables the controls by the manuals, after each operation, if the manuals are held operated too long. This feature is pertinent to a control mechanism embodying a single manual or pedal.

The invention consists in the novel features and in the combinations and constructions hereinafter set forth and claimed.

In describing this invention, reference is had to the accompanying drawings, in which like characters designate corresponding parts in all the views.

Figure 1 is a sectional view of the parts of this control mechanism, portions thereof through which the power is conducted, being shown diagrammatically.

Figure 2 is an elevation of parts shown in Figure 1, and in addition showing in section, ad-

2

ditional mechanism for preventing repeated operation, upon one operation of the manual or operator-operated control.

The invention, as here illustrated, embodies, generally, a master control member, a power motor for operating it to control the flow of power through the master control member to perform work, as to operate a machine, right and left hand manually-operated control members, a power line connected to the manually-operated control members individually, a transfer power line between the manual control members and having check devices in series therein capable of permitting a restricted flow of power through the check devices, there being one device for each manual control member, which are disposed reversely or in opposition to each other, so that one device restricts when the flow is in one direction but the flow is free in the other direction, and the other device restricts in the opposite direction and the flow is free in the first direction, a motor for operating the master valve connected in the transfer power line through the check elements, and a power-operated lock individual to each control member and connected to the transfer power line having the check devices, in such a manner that upon the operation of either manual member alone the other unoperated member is locked from operation. Also, the invention consists in an additional means for forcibly returning one of the manual control members to its original or starting position, controlled by the operation of the machine after it is operated a predetermined distance, so that repeated operations of the machine upon one operation of the manual, manuals or operator-operated member is prevented.

As the motive power is a pressure fluid, as compressed air, the control members, the check devices, the master control are shown as valves, and the motors, as pneumatic. The motors for operating the locks, etc., are shown as embodying diaphragms, and the check devices with the restricted flow around the checked main passages are shown as bleeder valves.

1 and 2 designate left and right manually-operated control valves enclosed in casing or boxes 3, 4. They are of the combined intake and exhaust type and may be of any suitable construction. The valves are alike in construction, and a description of the valve 1, which is shown in Figure 1, is sufficient for each.

5 designates the body of the valve, and 6 the movable valve member, this being shown as having a normally-closed intake head 7 at one end,

and a normally-open exhaust valve head 8 at the other end, and being reciprocally mounted in the casing 5, and the heads being connected by a stem. The intake valve head 7 is normally pressed against its seat in the valve casing 5 as by a spring 9, and when the head 7 is seated, the exhaust valve head is open for permitting the exhaust of air out through exhaust port 10 into the casing 3, which is open to the outer air. The air intake pipe 11, shown diagrammatically, is connected to a main line supply pipe L and opens into the intake end of the casing 5. An outlet or transfer pipe 12, shown diagrammatically, leads from an outlet port 13 in the valve casing 5 between the heads 7 and 8 or their seats. The valve member 6 is operated by a manual lever, the left hand manual being designated 14 and the right hand 15. Each lever is shown as in the form on an angle lever having an arm thrusting against a plunger 16, which in turn thrusts against a spring 17 in a socket or slide 18 having an axial extension 19, which thrusts against the exhaust head 8 of the valve member 6, the movement of the socket or slide 18 being against a return spring 20. The purpose of the spring 17, aside from cushioning, is to permit the forcible closing of the valve, when the manual 14 is held operated too long. For the purpose of further explanation, the parts corresponding respectively to the numerals 10, 11, 12 and 13 are designated in the right hand control valve as 10^a, 21, 22 and 23.

24 and 25 designate check valves having restricted passages around the checking means, as the balls therein, these devices being connected in series in the transfer power line through the valves 1 and 2 but reversely arranged in the line, so that when either control valve is open, the air will pass from the open control valve around the main passages and through the restricted passage of the check valve paired therewith and through the main passage of the other check valve to the other manually-operated valve, which is in closed position, and as it is in closed position, its exhaust is open, so that the air exhausts out and the flow of power to the motor for the master valve, to be described, is ineffective or not sufficient to operate it. For instance, assume that the left hand manual valve 1 only is operated, the air will then pass from the power line L, pipe 11, past the open intake valve head 7, out through the port 13, through pipe 12, check valve 24, through the restricted passage thereof, through the intermediate leg 26 of the line in which the two check valves are connected in series, thence through the main passage of the other check valve 25, then through line 22 of the other valve 2 and out through the exhaust port 10^a. If, however, the right hand valve 15 only is operated, air will pass from the supply line L through the line 21, past the open intake and exhaust valve head thereof through line 22, and around the main passage and through the restricted passage of the check valve 25, through line 26, through the main passage of the valve 24, then through the line 12 to the left hand valve 1, which is in closed position, so that the air exhausts out through the port 10 of the left hand manual 1. When, however, both valves are closed simultaneously or at the same operating period, the air pressure will pass through both lines 12 and 22 in opposite directions and build up the pressure in the intermediate leg 26 thereof and pass through line 27 to the pressure-operated motor 28, to be described, which operates

the master valve to the flow of air from the power line 29 out through a pipe or outlet 30 to a suitable motor, which operates the machine to which the control is applied. The check valves 24 and 25 are shown as having spring-pressed balls 300 for closing the main passages thereof against flow in one direction, and seats for the valves are formed with restricted passages 32, 33 therethrough, respectively, which are controlled or adjusted by metering pins or needle valves 34, 35. These check valves are so arranged that the check valves confine the flow from one control valve, as the left hand valve 1, toward the right hand valve 2 through the restricted passage 32 of the check valve 24 and through the main passage of the valve 25, while the valve 25 is located to restrict the flow from the valve 2 to the valve 1 through the restricted passage of the valve 25 and permit the passage from the valve 1 through the main passage of the valve 25. In other words, the check valves are reversely or oppositely disposed in the air circuit.

350 designates a normally-closed valve, which is connected by the pipe 29, previously referred to, to the main line, the movable valve member 36 of the valve 350 being pressed to closed position, as by a spring 37. The valve member 36 is operated to open the valve by a pressure-operated motor, previously referred to, including a diaphragm 38 in a diaphragm chamber 39, the pressure side of which is connected through the pipe 27 to the intermediate leg 26 of the power line in which the check valves 24, 25 are connected. The diaphragm operates a plunger 40 which, through suitable means, as a lever 41, opens the valve 350 when the diaphragm is energized. The valve member 36 also includes an exhaust valve head 42 normally spaced from an exhaust valve seat 43, the valve heads 42 and 36 being connected to operate as a unit. One arm of the lever 41 thrusts against a plunger 44 movable in the casing of the diaphragm chamber and thrusts against the valve head 42. The needle valves 34, 35 are adjusted so that the flow of air through the check valves 24 and 25, respectively, is less than the exhaust through the ports 10, 10^a of the valves 1 and 2, so that when only one control valve 1 or 2 is open, as the valve 1, most of the air will pass or exhaust out through valve 2, and when only the valve 2 is open, most of the air will exhaust out through the port 10 of the closed valve 1.

The means for locking either control valve 1 or 2 when the other valve only is operated, so that both valves must be operated simultaneously to effect the operation of the machine, consists in pressure-operated motors 45, 46 for the valves 1, 2 respectively, the motor 45 being connected by a pipe 47 to the line 22 leading to the valve 2, and the motor 46 for the valve 2 being connected by a pipe 48 to the line 12 of the circuit in which the check valves are connected in series, to the valve 1. Thus, upon operation of only one manual, as 14, for instance, the air will pass from the valve 1, which now is open, to the port 13, line 12, line 48 to the motor 46 and actuate it to move a locking member 49 into interlocking engagement with the movable valve member of the valve 2, and hence lock the valve 2 operated by the manual 15 from operation. If, however, the manual 15 is first operated, then the air passes from the line 22 leading from the now open valve 2 to the motor 45 through pipe 47, causing the locking member 50 thereto to interlock with the movable valve member of valve 1 and lock it

from operating movement. The motors 45, 46 are alike in construction, and each includes a diaphragm 500 in a diaphragm chamber 51, the pressure side of which is connected to the pipe 47 or 48. The diaphragm acts on a sliding plunger 52 which acts upon the locking bolt 49 or 50 to move it against the action of a returning spring 53 or 54. Thus, the machine can not be operated upon movement of only one manual. If only one manual is operated, the other is immediately locked from operation, so that the operated manual must be permitted to return to starting position, and both manuals then operated simultaneously to effect the operation of the machine.

Upon the release of the manuals, the air is free to exhaust back through the exhaust ports 10, 10^a of the manually-operated valves 1 and 2, thus exhausting the air from the diaphragm chamber 39 and permitting the master valve to open. This in turn permits the air to exhaust back through the pipe from the Servo motor of the machine.

The control mechanism here shown is more particularly adapted for presses, as punch presses, in which a complete operating movement is without a stop or pause, when the press is in closed position. When this mechanism is used in presses, as garment presses, where the press remains closed, suitable releasably holding means of the type well known in the art is provided to lock the press closed or to lock the control valves in closed position, until released.

In some cases, it is desired to positively prevent repetition of the press operation upon one operation of the control or controls, if a two hand control is used, and in this embodiment of my invention, this is shown as means for forcibly returning the control member or valve or one of the two control valves to closed position, this means being controlled by the operating movement of the machine or some part thereof, as a movable part of the Servo motor or a connection operated in synchronism therewith. The Servo motor is, for illustration only, shown as of the cylinder and piston type, the piston being single acting. The piston rod is shown as connected to a motion transmitting part, which also operates the mechanism for forcibly opening the control valve or one of the two control valves. 55 designates the cylinder to which the feed pipe 30 is connected, and 56 designates the piston rod which is at the end of its power stroke when the pressure in the cylinder 55 is released and the air is free to exhaust back through the pipe 30. The piston is retracted in any suitable manner by a spring 57. When the piston reaches the end of its power stroke, it starts to effect the operation of the means for forcibly restoring the valve or one of two valves to closed position. As here shown, this mechanism includes a diaphragm motor 59, similar to the motor for the diaphragm 500 and operating a push plunger 60 which, through suitable leverage 61, operates to withdraw the valve 2 from open to closed position, against the reaction of spring 18 (see Figure 1) which holds the plunger 16 from movement, so that the valve 2 is forcibly opened from open to closed exhaust position, when the piston is approaching the end of its power stroke. The air to the diaphragm mechanism 59 is controlled from the power line through pipe or line 62 to the end of a valve casting 63 in which a spring-pressed combined intake and exhaust valve member 64 is located with the intake head 65 normally closed and the exhaust valve head 66 normally spaced from its seat 67.

The motion transmitting member 58 coacts through a sliding pin 68 with the movable valve member, as the piston approaches the end of its power stroke, and operates said valve member to close the exhaust valve head 66 and open the intake, and thus permit the air to flow through the valve 63 from the pipe or line 62 and through the line 69 to the diaphragm chamber of the device 59.

- 10 In Figure 2, all parts corresponding to the parts in Figure 1 bear the same reference numerals. The operation of the form shown in Figure 2 is the same as that shown in Figure 1, but with this addition, that when the motor of the machine 15 completes its power stroke, the valve head 65 is opened by the movement of the piston rod 56 or some motion transmitting part or other part of the machine operated thereby, to permit air to flow from the main pipe line through the valve 20 63 to the diaphragm chamber of the motor 59 to actuate mechanism, as the lever 61, to forcibly open the valve 2, or some valve corresponding thereto, against the force of the operator holding it closed. This operation causes the exhaust port 25 of this valve 2 to be opened, permitting air to exhaust from the diaphragm chamber 28 of the master valve and the master valve to close, and hence to open its exhaust port, letting the air exhaust from the cylinder back through the pipe 30 and out past the open exhaust valve head 42. Hence, to again operate the press, the manual or 30 manuals, if there are two, must be again operated. This mechanism for forcibly opening a control 35 valve in the event the operator holds it operated too long is applicable also to machines having a single control valve or a single pedal-operated control valve.

What I claim is:

1. In a two hand control mechanism, right and 40 left hand manually operated self-returning control valves of the combined intake and exhaust type connected to a fluid pressure supply line and normally in closed position in which the intake is closed, each control having a normally open 45 exhaust port, a self-closing master valve connected in a pressure fluid supply line and normally in closed position, a pressure fluid motor operable to open the master valve, a check valve paired with and located in a line in series with each 50 manual control valve, each check valve having its valve member arranged to check the flow of fluid from its companion control valve when the companion control valve is open, and having a restricted open by-pass around its check member 55 to the outlet end of the check valve, the outlet ends of the check valves being connected by a conduit to permit the fluid by-passing either check valve to pass out the exhaust port of the other manual control valve when the latter control valve is closed, and motive fluid operated 60 means for locking the control valves in starting position, the lock means for the right hand valve being connected in multiple in the line connected to the check valve paired with the left hand valve, the lock means for the left hand valve being connected in the line to the check valve paired with the right hand control valve, the motor for the master valve being connected to the pipe conduit connecting the outlet ends of the check 65 valves.
2. The construction set forth in claim 1 and in addition means for forcibly returning one of the manually operated valves to its normal or starting position including a pressure fluid motor and 70 a valve operated by the operating movement of

the servo motor during each operation for supplying motive fluid to the last mentioned motor, whereby repeated operations upon the manual valves operated is prevented.

3. In a two hand control for a motor which operates a master control member to control the flow of motive fluid to a servo motor of a machine; right and left hand manually operated control members normally in position to cut off the flow of motive fluid, a motive fluid line connecting the manually operated control members in series and having oppositely operating check elements therein, one for each manual control member, each element being arranged to check the flow of fluid from its companion manually controlled member to the other check element, and each check element having a restricted bypass for the motive fluid around its check means, whereby some of the motive fluid less than the full capacity of the fluid line by-passes around the check elements when either of the manuals is operated to permit the flow of motive fluid, the unoperated manual permitting the escape of the by-passed fluid when only one manual control member is operated, a motive fluid line for the motor connected to the line connecting the check elements, all whereby when both manual control elements are operated the motive fluid passes at full capacity through both manual control members and the check elements to the motor for the master control member, and the master control member operated to conduct the motive fluid to the servo motor, a lock for each manual member including a motive fluid operated motor,

the motor for the lock of the right hand manual control member being connected to the line leading to the check element for the left hand manual control member, and the motor for the lock

5 of the left hand manual control member being connected to the motive fluid line leading to the check valve paired with the right hand manual control member so that upon the operation of either manual control member only, the other manual control member is locked from operation.
